UNITED STATES PATENT OFFICE.

FREDERICK G. SIMPSON, OF SEATTLE, WASHINGTON.

WIRELESS TELEGRAPHY.

1,189,881.

Specification of Letters Patent. Patented July 4, 1916.

Original application filed November 1, 1912, Serial No. 729,064. Divided and this application filed April 23, 1913. Serial No. 763,142.

To all whom it may concern:

Be it known that I, FREDERICK G. SIMPSON, a citizen of the United States, residing at Seattle, in the county of King and State 5 of Washington, have invented certain new and useful Improvements in Wireless Telegraphy, of which the following is a specification.

This application is a division of one filed 10 by me Nov. 1, 1912, Serial No. 729,064.

The invention herein disclosed relates to certain improvements in circuiting and apparatus for the reception of signals of the Hertzian wave type.

15 The present invention has for its object the provision of a new and improved means for detecting the existence of and utilizing to the best advantage voltages or currents, in wireless telegraph receiving circuits, which 20 have been generated within such circuits by the passage of a train of Hertzian waves.

The invention therefore consists in the circuiting and arrangement and combination of apparatus therein substantially as 25 hereinafter set forth and claimed.

In the accompanying drawing, which forms a part of this specification, Figure 1 30 diagrammatically depicts the improved circuiting and the principal features of the receiving instrument employed therewith; and Fig. 2 is a transverse sectional view of the electromagnet in the main receiving circuit.

For a more complete description of the 35 details of said instrument reference may be had to my earlier application above referred to.

In the graphic illustration of the receiving circuit, 30' and 30'' indicate parallel, 40 magnetizable, vibratory reeds fixed at one end and attached at the other to an adjustable block 31 of insulation. This block is attached to the crosshead 37 mounted in frame 34 and is adjustable by means of 45 screw 30 and spring 35. Thus the tension of the reeds may be regulated. The slides 11 carry arms 14, which bear against the reeds. These slides are joined by a left and right hand screw 44 by which they may be ad- 50 justed toward and from one another to vary the length of the portions of the reeds left free to vibrate. The microphonic contacts *a* and *b*, actuated by the reeds are on the ends of the pins 16'' and 16'. The char- 55 acteristics of other features of the apparatus

and circuiting will be described in the detailed operation of the invention.

The aerial here shown is of the antenna form indicated at 52, to which is connected the variable inductive coupling having a primary 51^p and a secondary 51^s. The antenna 52 is grounded through primary 51^p of the inductive coupling 51. Hertzian waves arriving at the antenna induce voltages therein, which cause high frequency oscillating currents to flow through the antenna and the primary to and from the earth. These currents, by inductive action through the coupling 51, produce voltages within the secondary, or main receiving circuit, containing the coil 51^s, the fixed condenser 53, the solenoid coil of helix 19, and the electro-magnet coil 17, whose core consists of fine individually insulated iron wires, Fig. 2. The primary 51^p and secondary 51^s permit of adjustment of inductance in the regulation of the flow of high frequency current over said receiving circuit.

80 A crystal detector of well-known type is indicated at 61 connected in parallel circuit with the coils 19 and 17 of the micro-magnetic detector. In this association the micro-magnetic detector is especially effective in forming a means of adjustment for some 85 particular wave train frequency, and also as a means of amplifying the strength of the received signal by its action as a relay, permitting energy from the battery or other electrical generator 57, to furnish energy required by the telephone receiver 59 or other indicating instrument in its production of 90 audible or visible signals. By this use of the crystal detector, unidirectional pulsating currents only are permitted to flow through coils 19 and 17. The action of a pulsating current, flowing through said coils, upon the reeds 30' and 30'' is to all practical purposes 95 the same as is that of an alternating current of the same frequency.

100 Reed 30' lies within the magnetic field of the electro-magnet coil 24 wound about the adjustable core 23. This magnet is excited by current from battery 56. The voltage at the terminals of coil 24 is capable of adjustment through the medium of the regulating rheostat 55. The density of the magnetic field in the vicinity of 30' can be regulated 105 by variation of the exciting current and also by movement of the core 23.

Pulsating currents of high frequency flowing through coils 19 and 17 produce motion in the reeds 30' and 30''. In the absence of these currents the reed 30' is moved slightly 5 away from its position of normal rest by the magnetic attraction of the core 23 of magnet 24, and a state of magnetic polarity exists within the reed 30' at a point opposite core 23. Magnetism is also communicated to a 10 lesser degree to the core of coil 17. Upon the arrival of a series of Hertzian waves, high frequency pulsating currents flow through coils 19 and 17, which in effect partially suppress the magnetic condition of 15 the reed 30' and the core 18, respectively, permitting reed 30' because of mechanical tension thereon to recede slightly from the magnet core 23. At the same instant the high frequency currents flowing through 20 coil 17 induce within the core 18 an oscillating magnet flux, which has an integrating tendency to attract reeds 30' and 30'' to its extremities. These phenomena are simultaneous in their action and have a tendency 25 to draw said reeds closer together, thereby decreasing the resistance at the microphonic contacts *a* and *b*, which permits an increased flow of current from the generator 57 through the reeds, the pins 16' and 16'', the 30 microphonic contacts and the primary of transformer 58. This increase of current by inductive action produces a voltage between the secondary terminals of the transformer 58 thereby causing current to flow in 35 the secondary to produce an audible signal in the receiver 59. As each series of Hertzian waves communicate but a single impulse to the reeds, each will, if properly proportioned, vibrate at the frequency of 40 the wave trains, *i. e.* at the same rate per second of vibrations as is the rate per second in the number of wave trains arriving at the receiving station. For the purpose of securing the greatest efficiency in operation 45 of the micro-magnetic detector described, it is necessary that the reeds be of such dimensions that their natural period of vibration shall be the same as the frequency of the incoming wave trains. Then by the use of 50 proper adjusting devices the active lengths and tension of the reeds may be so regulated that the reeds will respond accurately to wave trains arriving at a preselected frequency and will not be affected by wave 55 trains arriving at a different frequency. This adjustment to the frequency of wave trains is entirely mechanical and should not be confounded with the adjustment for electrical resonance by properly proportioning the capacity and inductance in the receiving circuit, which adjustment is entirely electrical and is made for the frequency of the oscillations within the wave trains themselves, or 60 in other words, for the wave length of the 65 Hertzian waves.

The invention claimed is:—

1. In a wireless telegraph system, the combination with an antenna and a receiving circuit, two suitably supported reeds made of magnetizable material, a helix surrounding 70 a portion of one of said reeds, an electromagnet in the receiving circuit disposed to extend between said two reeds so that each of the poles of its core may be adjacent to one of said reeds whereby said electro-magnet may be operated to attract said reeds to bring them nearer to each other, said helix and electromagnet being in series in the receiving circuit, microphonic contacts operated by said reeds, a condenser connected 75 with said circuit in series with said helix and said electro-magnet, a detector connected with said circuit in parallel with said helix and said electro-magnet, and a signal controlled by the microphonic contacts. 80

2. In a wireless telegraph system, the combination with an aerial and a receiving circuit deriving current therefrom, of a crystal detector in parallel with the receiving circuit, a vibrator, an actuating electro-magnet therefor consisting of a coil of fine wire in series in said circuit and having a core of fine individually insulated iron wires, a condenser in said circuit in series with said coil, and a helix in series with said coil for 90 magnetizing said vibrator, the helix and coil in series with said receiving circuit. 95

3. In a wireless telegraph system, the combination with an aerial and a receiving circuit deriving current impulses therefrom, a 100 receiving instrument having a vibratory magnetizable reed, a helix in said circuit surrounding said reed, an electro-magnet whose coil is in series with said helix and whose core is a bundle of fine individually 105 insulated iron wires located to attract said reed, and a condenser in said circuit in series with said coil, of a crystal detector in parallel with said coil and said helix. 110

4. In a wireless telegraph system, the combination with an aerial and a receiving circuit deriving current therefrom, a vibrator forming part of a micro-magnetic receiving instrument, a movable helix in said circuit and surrounding a portion of said vibrator 115 for magnetizing it, an electro-magnet whose coil is in series with said helix and whose core is a bundle of fine individually insulated iron wires located to attract said vibrator, and a condenser in said circuit in 120 series with said coil, of a crystal detector in parallel with said coil, and a separate circuit containing an electro-magnet whose field embraces said vibrator and said fine wire core. 125

5. In a wireless telegraph system, the combination with an aerial and a receiving circuit, of a rectifier of the crystal type for alternating currents, and a condenser in series with the receiving circuit associated with a vibrator element, a helix in the re- 130

ceiving circuit and surrounding a portion of said element, an electro-magnet in the receiving circuit and having one of its poles adjacent to said element, whereby when 5 rectified electro-magnetic waves exist in the receiving circuit the helix and electro-magnet are caused to directly vibrate said element, means in a separate circuit to produce a magnetic field of predetermined 10 polarity in and adjacent to said element, microphonic contacts operable by said element, and a signal operated by said contacts.

6. In a wireless telegraph system, the 15 combination with an antenna and a receiving circuit, two suitably supported reeds made of magnetizable material, a helix surrounding a portion of one of said reeds, an electromagnet in the receiving circuit 20 disposed to extend between said two reeds so that each of the poles of its core may be adjacent to one of said reeds whereby said electromagnet may be operated to attract said reeds to bring them nearer to each 25 other, said helix and electromagnet being in series with the receiving circuit, microphonic contacts operated by said reeds, indicating means controlled by said contacts, a condenser connected with said circuit in series with said helix and said electromagnet, of a detector connected with said circuit in parallel with said helix and said electromagnet, and a signal controlled 30 by the microphonic contacts.

35 7. In a wireless telegraph system, the combination with an aerial and a receiving circuit, of a detector in parallel with the receiving circuit associated with a plurality of adjustable vibrator elements, indicating 40 means controlled by said elements, a helix in the receiving circuit surrounding a portion of one of said elements, an electromagnet having its poles adjacent to and located between said vibrator elements, and a condenser in series with the helix and electromagnet in said receiving circuit.

45 8. In a wireless telegraph system, the combination with an aerial and a receiving circuit, of a detector in parallel with the receiving circuit associated with an adjustable magnetizable reed provided with microphonic contacts, a signaling circuit connected with said contacts, means in the receiving circuit to vary the hysteresis in 50 and to directly actuate, said reed on the passage of electromagnetic waves, adjustable means in a separate circuit to produce a desired degree of magnetization in said element, and a condenser in series with said 55 means in the receiving circuit.

60 9. In a wireless telegraph system, the

combination with an aerial and a receiving circuit, of a detector in parallel with the receiving circuit associated with a plurality of magnetizable reeds, indicating means 65 controlled by said reeds, a movable helix surrounding a portion of one of the reeds, an electromagnet in series with the helix and the receiving circuit to directly vary the hysteresis of said reed, means in a separate 70 circuit to produce a predetermined polarity of magnetism adjacent to and whose field includes the reed, whereby on the passage of electromagnetic waves through the receiving circuit, the helix and electromagnet 75 are caused to rapidly vary the hysteresis, and a condenser in series with the helix and electromagnet.

10. In a wireless telegraph system, the combination with an aerial and a receiving 80 circuit, of a detector in parallel with the receiving circuit associated with a magnetizable and adjustable vibrator element, indicating means controlled by said element, means in the receiving circuit to immediately 85 magnetize different portions thereof and to directly actuate said element by rectified electromagnetic waves, a separate circuit, means in the separate circuit to produce a magnetic field to said element, whereby on the passage of electromagnetic waves 90 through the means in the receiving circuit, the integrating effect produced by varying the hysteresis in the element is to cause said element to vibrate at its free frequency 95 corresponding to the frequency of the electromagnetic wave trains impressed, and a condenser in series with the receiving circuit.

11. In a wireless telegraph system, the 100 combination with an aerial and a receiving circuit, of a detector in parallel with the receiving circuit associated with a plurality of adjustable reed vibrator elements capable 105 of magnetization, signaling means controlled by said elements, a plurality of instrumentalities in the receiving circuit to produce magnetic polarities in separate and distinct portions thereof and capable of actuating said element by the passage of electromagnetic 110 wave trains, means to magnetize another portion of said element by producing a magnetic field of predetermined polarity adjacent thereto, and a condenser in series 115 with said instrumentalities in said receiving circuit.

Signed at Seattle, Wash., this 15th day of April, 1913.

FREDERICK G. SIMPSON.
